PAPER MAKING MACHINERY

Joseph E. Bond, Middletown, Ohio

Application October 19, 1938, Serial No. 235,727

5 Claims. (Cl. 92—20)

This invention relates to pulp handling apparatus for disintegrating and agitating paper pulp or the like.

One object of the invention is the provision of an apparatus for handling paper pulp or the like and embodying shredding and disintegrating blades and impelling means so arranged as to receive pulp from the discharge end of a circulating tank and return the pulp to a point in the circulating tank at the supply end thereof which is below the normal level of material in the circulating tank, a portion of the pulp that passes the disintegrating and impelling blades being supplied to an auxiliary impelling means and supplied to a point above the level of material in the tank so as to fall on the circulating material at a point between the supply end and the discharge end of the tank.

Another object of the invention is the provision of a pulp handling apparatus embodying a plurality of impeller chambers through which the pulp is successively passed so as to travel in opposite directions along a common shaft on which the impellers are provided whereby the end thrust on the shaft produced by the action of one impeller will be balanced or counteracted by the thrust of another.

Another object of the invention is the provision of an apparatus of the character mentioned in which stationary blades are provided adjacent an impeller and cooperating therewith so that any small pieces of pulp passing the impeller will be subjected to a shredding or disintegrating action and so arranged as to stop the whirling action of the pulp as it leaves the impeller.

Other objects and advantages of the invention will be apparent from the following description, the appended claims and the accompanying drawings in which—

Fig. 1 is a top plan view of a pulping apparatus embodying the present invention;

Fig. 2 is a side elevation of the pulping apparatus;

Fig. 3 is a section on the line 3—3 of Fig. 1;

Fig. 4 is a section on the line 4—4 of Fig. 3 and

Fig. 5 is a section on the line 5—5 of Fig. 3.

Referring more particularly to the drawings by reference numerals, 10 generally designates the main circulating tank of a pulping apparatus adapted for handling paper pulp to be defibered, pulped or agitated. Pulp laps or stock pieces may be supplied to the tank at a suitable location between the supply end 11 and the discharge end 12 and may circulate around the inner wall

portions 13 in the direction of the arrow shown in Fig. 1 by gravity action, the floor 14 being arranged at a suitable inclination and at a suitable height at the supply end 11 above the discharge end 12 so that the stock may circulate and flow into a receiver 16. The opening into the receiver 16 is of large size, the upper inclined wall 17 of the tank inclining downwardly as shown in Fig. 2 so that a free and substantially unobstructed passage is provided.

Within the receiver 16 is a shaft 18 operated at high speed by a suitable motor 25 and having a series of stock disintegrating and pulping blades 19. The ends of the blades 19 which are first engaged by the pieces of pulp entering the receiver are spaced at a considerable distance from the walls 20 of the receiver so that the stock will be whirled, shredded and broken up into comparatively small pieces before the stock flows through the tapering passage 21 and into the discharge passage 22. The distance between the ends of the blades 19 and the walls of the passage 21 decreases as the blades approach the throat of the passage to give a progressively increasing confining action on the pulp pieces as they are reduced in size in moving along the passage. The stock is forced along into the discharge passage by means of impact impeller blades 23 which operate rather closely to the cylindrical end of the throat 21.

Adjacent the terminal end of the cylindrical portion of throat 21, the walls of the throat are provided with inwardly extending blades 24 of any suitable number, two such blades being shown in Fig. 5. The blades cooperate with the edges of the impeller blades 23 so that any small pieces of pulp passing between the blades 24 and the blades 23 will be torn apart without substantial cutting action. The minimum spacing between the outermost portions of the blades 24 and the edges of the blades of the impeller 23 is not less than one-sixteenth of an inch or may be somewhat greater than that and even up to about one-quarter of an inch so that any substantial cutting action is eliminated although the blades 24 operate to provide a disintegrating action to any of the larger pieces of pulp and also are effective in stopping the rotational whirling of the pulp as it leaves the end of the throat 21. The end of the throat is also provided with an annular ring 25' whose inside diameter is somewhat less than the inside diameter of the throat 21 to direct the flow from the walls of the throat 21 somewhat towards the axis of the shaft on which the impeller blades are provided.

A large part of the stock entering the discharge passage 22 flows upwardly through a flaring outlet pipe which extends to the supply end of the tank 10, emptying into the tank at a point below the normal level of the material in the tank. As shown in Fig. 2, the discharge passage 22 is of short length and extends up to an opening in the bottom floor portion of the tank so that the impact impeller 23 is only called upon to produce enough pressure to raise the stock at the desired rate of flow against the head existing in the tank at the supply end.

Some of the stock pieces that pass the impeller 23 may be of substantial size after passing only once into the zone of treatment where they are acted on by the blades 19, but the stock may circulate a number of times around the tank and from the supply end of the disintegrating and impelling blades 19 and 23 back through the discharge passage 22 so that eventually the stock pieces will be reduced to a condition fine enough to be used in the manufacture of paper or other fibrous sheets.

In order that the large pieces passing the impeller 23 will be more effectively broken up and disintegrated, the discharge passage 22 of the first impelling means communicates by means of the pipe 27 with the second impeller chamber 28 shown in axial spaced relation with respect to the first impeller 23. The shaft 18 which carries the impeller 23 also carries impact impeller blades 29 in the second impeller chamber 28, the blades of the impeller 29 being inclined oppositely with respect to the inclination of the blades of impeller 23 so that while the impeller 23 operates to force material towards the left as viewed in Fig. 3, the impeller 29 forces the material toward the right and into the discharge passage 30 of the second impelling means. The endwise thrust created on the shaft 18 by the action of the impeller 23 is thus counteracted by the oppositely directed thrust of impact blades 29, and the bearings of the shaft 18 are thus relieved from any large endwise thrusts.

Adjacent the edges of the blades 29 of the second impact impeller there is a series of stationary blades 32 arranged in the casing walls 33 which provide an enclosure serving as the discharge passage of the second impeller. These blades 32, as shown in Figs. 3 and 4, extend substantially radially so as to project inwardly beyond the outer ends of the impact impeller blades, the edges 35 of the stationary blades being spaced a small distance of at least one-sixteenth of an inch or up to one-quarter inch from the edges 36 of the impact impeller blades 29 so that any small pieces of pulp will be effectively disintegrated and torn apart, without substantial cutting action, as those pieces pass from the supply end to the discharge end of the second impeller. They also serve to stop the rotational whirling of the pulp as the pulp enters the discharge passage 30. The outer sides of the blades 32 are interconnected by a baffle wall 37 which directs the flow of material inwardly towards the shaft axis. The blades 32 and the baffle wall 37 are preferably made integral with an outer flanged ring to form a readily replaceable unit that may be bolted in place between flanged portions of the casing structure, as shown in Fig. 3.

The impeller 29 receives stock under some substantial pressure produced by the impact impeller 23, and supplies the stock to the discharge passage 30, which is separated from the discharge passage of the first impeller by means of a parti-

tion wall 38. An outlet pipe 39 however extends from the discharge passage 30 so that the stock after passing into the discharge passage 30 can be supplied to a suitable point above the level of the material in the circulating tank and act as a submerging stream, falling onto stock pieces that may be floating on the surface of the material in the tank and thus submerging the floating pieces. The pieces are thus submerged so that they may more readily pass down through the inclined passage and into the receiver 16. The pipe 39 which carries the stock from the discharge passage 30 of the second impeller, as shown in Figs. 1 and 2, extends upwardly between the supply and discharge ends of the tank and then projects substantially horizontally above the top of the tank, as indicated at 40, and discharges into a conduit 41 which extends transversely preferably the full width of the supply end of the tank. The lower wall of the conduit 41 is provided with a passage or slotted opening 42 extending across the tank, the conduit 40 being arranged at a suitable location between the supply and discharge ends of the tank and preferably just ahead of the upper end of the inclined wall 17 so that the submerging stream which falls downwardly through the slot 42 and onto the circulating material in the tank, or pulp laps that have just been added, will effectively submerge floating stock pieces and cause them to travel more readily down under the inclined wall 17.

The horizontally extending portion 40 of the pipe 39 is preferably provided with a control valve 43 which is operated manually or otherwise to control the rate of flow into conduit 41. Adjacent the upper end of the pipe 39 the latter may also communicate with an auxiliary or branch pipe 44 having a control valve 45 and extending to a point above the stock level in the tank and near the supply end of the tank. Some suitable quantity of stock may thus be supplied to the upper level of stock near the supply end of the tank while the main flow of stock into the tank comes upwardly through the larger supply pipe 22, the added flow through pipe 44 providing a more thorough mixing action especially when the apparatus is used for deinking or agitation purposes. The relative sizes and capacities of the pipes or passages 39 and 22 and of the impelling means for forcing material through those pipes or passages is such that about 90% of the stock circulated in the tank will flow up through the passage 22 while the remainder is supplied through the second impact impeller and flows upwardly through the pipe 39 and is then returned to the circulating material in the tank. The impact impeller 29 is called upon to raise the stock to a higher level than the stock is raised by the impact impeller 23, but since the impact impeller 29 handles only a small part of the stock handled by the first impact impeller, and since it is supplied with stock under a pressure corresponding to that which exists at the discharge side of the first impeller, it will be apparent that neither of the successively acting impeller means is called upon to raise the material which it handles to an unnecessarily large height.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. Pulp handling apparatus of the character described comprising a first chamber having inlet and outlet passages, a circulating tank for receiving material from the outlet passage and circulating the material to the inlet passage of said first chamber, a shaft rotatable in said chamber and provided with impact impeller blades having propulsive surfaces inclined to the plane of rotation to force the material handled in one direction along the shaft from the inlet to the outlet passage of said chamber, an auxiliary chamber having an inlet passage communicating with the outlet passage of said first chamber at a point ahead of the tank and having an outlet passage extending to the tank above the level of the material in the tank, and auxiliary impact impeller blades on said shaft having inclined propulsive surfaces for forcing material in an opposite direction along the shaft to the outlet passage of the auxiliary chamber.

2. Pulp handling apparatus of the character described comprising a first chamber having inlet and outlet passages, a circulating tank for receiving material from the outlet passage and circulating the material to the inlet passage of said first chamber, a shaft rotatable in said chamber and having a series of stock disintegrating blades for whirling and shredding stock pieces supplied thereto and provided with impact impeller blades having propulsive surfaces inclined to the plane of rotation to force material in one direction along the shaft from the inlet to the outlet passage of said chamber, an auxiliary chamber having an inlet passage communicating with the outlet passage of said first chamber at a point ahead of the tank and having an outlet passage extending to the tank above the level of the material in the tank, auxiliary impact impeller blades on said shaft having inclined propulsive surfaces for forcing material in an opposite direction along the shaft to the outlet passage of the auxiliary chamber, and stationary blades having edges arranged closely adjacent the discharge edges of the auxiliary impact impeller blades for disintegrating material passing said auxiliary blades.

3. Pulp handling apparatus of the character described comprising a first chamber having inlet and outlet passages, a circulating tank for receiving material from the outlet passage and circulating the material to the inlet passage of said first chamber, said tank having an inclined floor sloping downwardly to the said inlet passage and having a substantially horizontal opening in said floor at one end thereof, a supply pipe having its upper end terminating at said opening and communicating at its lower end with the outlet passage of said first chamber, a shaft rotatable in said chamber and provided with impact impeller blades having propulsive surfaces inclined to the plane of rotation to force the material handled in one direction along the shaft from the inlet to the outlet passage of said chamber, an auxiliary chamber having an inlet passage communicating with the outlet passage of said first chamber at a point ahead of the tank and having an outlet passage extending to the tank above the level of the material in the tank, and auxiliary impact impeller blades on said shaft having inclined propulsive surfaces for forcing material along the shaft to the outlet passage of the auxiliary chamber.

4. Pulp handling apparatus of the character described comprising a first chamber having inlet and outlet passages, a circulating tank for receiving material from the outlet passage and circulating the material to the inlet passage of said first chamber, said tank having an inclined floor sloping downwardly to the said inlet passage and having a substantially horizontal opening in said floor at one end thereof, a supply pipe having its upper end terminating at said opening and communicating at its lower end with the outlet passage of said first chamber, a shaft rotatable in said chamber and provided with impact impeller blades having propulsive surfaces inclined to the plane of rotation to force the material handled in one direction along the shaft from the inlet to the outlet passage of said chamber, an auxiliary chamber having an inlet passage communicating with the outlet passage of said first chamber at a point ahead of the tank so as to be subjected to the pressure created by the impact impeller blades in said first chamber, said auxiliary chamber having an outlet passage extending to a point between the supply end and the discharge end of the tank above the normal level of material at such point for supplying the material from said second chamber onto the material in the tank, and auxiliary impact impeller blades on said shaft having inclined propulsive surfaces for forcing material in an opposite direction along the shaft to the outlet passage of the auxiliary chamber.

5. Pulp handling apparatus of the character described comprising a first chamber having inlet and outlet passages, a circulating tank for receiving material from the outlet passage and circulating the material to the inlet passage of said first chamber, said tank having an inclined floor sloping downwardly to the said inlet passage and having a substantially horizontal opening in said floor at one end thereof, a supply pipe having its upper end terminating at said opening and communicating at its lower end with the outlet passage of said first chamber, a shaft rotatable in said chamber and provided with impact impeller blades having propulsive surfaces inclined to the plane of rotation to force the material handled in one direction along the shaft from the inlet to the outlet passage of said chamber, an auxiliary chamber having an inlet passage communicating with the outlet passage of said first chamber at a point ahead of the tank so as to be subjected to the pressure created by the impact impeller blades in said first chamber, said auxiliary chamber having an outlet passage extending to a point between the supply end and the discharge end of the tank above the normal level of material at such point for supplying the material from said second chamber onto the material in the tank, and having a branch discharge passage, a distributing tank above the level of material in said tank adjacent the discharge end of the tank and in communication with said branch discharge passage for projecting a stream of material the width of the tank at such point onto the material in the tank, and auxiliary impact impeller blades on said shaft having inclined propulsive surfaces for forcing material along the shaft to the outlet passage of the auxiliary chamber.

JOSEPH E. BOND.
